UNITED STATES PATENT OFFICE.

GUSTAVE KAHN, OF DETROIT, MICHIGAN.

WINDOW.

1,101,187.

Specification of Letters Patent. Patented June 23, 1914.

Application filed July 10, 1913. Serial No. 778,267.

To all whom it may concern:

Be it known that I, GUSTAVE KAHN, a citizen of the United States, and a resident of Detroit, in the county of Wayne and State 5 of Michigan, have invented a new and Improved Window, of which the following is a specification.

This invention relates to the construction of windows, particularly to means for supporting ventilator sashes; and its object is to provide an efficient and strong connection 10 between the main and ventilator portions of window sashes, which may be cheaply constructed, and which will admit of ready 15 mounting and demounting of the ventilator portion of the window.

This invention consists specifically, in securing a flanged bar to the inner edges of the lower half of a window sash having an aperture 20 in which a ventilator sash is to be mounted and in forming the upper ends of said bar into concave seats; and in securing a similar bar around the outer edges of the upper half of said ventilator sash and so 25 forming the lower ends of said second bar that these ends may act as trunnions for the ventilator sash and rest in said seats.

It consists broadly in the combination of curved seats secured to the edges of one 30 sash and rounded trunnions on the edges of another sash, together with contact strips mounted on both sashes, one of said sashes being mounted in an aperture in the other.

In the accompanying drawings, Figure 1 35 is a front elevation of a window constructed embodying the present invention. Fig. 2 is a perspective of a seat secured to the inner edge of an apertured window sash. Fig. 3 is a perspective of a trunnion secured to 40 the outer edge of a ventilator sash. Fig. 4 is a section on the line 4—4 of Fig. 1 on a larger scale. Fig. 5 is a rear view of one of the inner muntins of the main sash and the adjacent outer side bar of the pivoted sash. 45 Fig. 6 is a detail of the pivot.

Similar reference characters refer to like parts throughout the several views.

The sashes that embody this invention may be of any desired construction, those 50 shown in the drawings being of the type shown in my prior Patent Number 1,018,503, dated February 27, 1912. The main sash consists of outer bars 5—6—7 and 8, longitudinal cross bars 9 and 10, and the muntins 55 11 and 12. Within the opening between the bars 9, 10, 11 and 12 is pivoted a ventilator sash consisting of side bars 13 and 14, top

bar 15, bottom bar 16, muntin 17 and horizontal cross bar 18. It will be understood that the construction shown is merely an 60 example and that the invention may be embodied in a window whose main and ventilator sashes are made up of any desired number of muntins and cross bars.

The side bars, top bars and bottom bars 65 are shown formed of T bars, with flanges 20, against which channel bars are secured, preferably by rivets 21 extending through the webs 23 of the T bars and webs 22 of the channel bars. The flanges 24 of these 70 channel bars are wider than the flanges 25, and the narrower flanges are in contact with the flanges 20 of the T bars. As stated before, these channel bars extend around the opening in the main sash, the lower bar 75 26 being secured to the main sash and the upper bar 27 to the pivoted sash. The upper ends of the lower bar 26 are cut to fit the cylindrical lower ends of the bar 27 on the pivoted sash, as shown in Figs. 2 and 3, the 80 wider flange 24 of the upper bar being preferably bent to form the trunnions for the pivoted sash. The flange 24 is cut away at these points in order that it may pass the web 23 on the T bars, when the pivoted sash 85 is swung out of the plane of the main sash. A screw 28 may be mounted in each of the muntins 11 and 12. When the sashes are completed, the bars 26 and 27 are secured to them and the ventilator or inner sash is 90 mounted in position with its trunnions 29 resting in the seats 30 on the main sash. The screws 28 are then turned in until they contact with the web 22 of the bar 27, just above the trunnions. As the flange 24 is 95 cut-away at 29 at each side of the pivoted sash, that portion of the bar 27 can pass the adjacent flange 20 of the muntin 11 or 12, and the inner sash can freely swing to the position indicated in Fig. 6. 100

It will be noticed in Fig. 6 that the bar 27 is no longer resting in the seat 30, but on the upper edge of the flange 24. The shoulders 31 (Fig. 3) adjacent the trunnions contact with the rear edge of the webs 23 of the 105 adjacent muntins 11 and prevent the pivoted sash moving to the right in Fig. 6, while the screws 28 prevent movement in the opposite direction. When the sashes are in the positions shown in Fig. 6, the point of support is nearer the top bar 15 than when in the positions shown in Fig. 4. As a result, the pivoted sash is more inclined to swing to 110 vertical position.

Referring now to Fig. 4, it will be noted from the dotted lines, which are drawn from the center of the trunnions and seats, that when the pivoted sash swings from inclined 5 to upright position, the flange 25 of the upper channel bar 27 will contact with the inwardly projecting flanges 20 of the upper portions of the muntins 11 and 12 and of the top cross bar 10; that the flange 24 of this 10 channel bar will contact with the rear edges of the webs 23 of these members 10, 11 and 12; that the rear edges of the webs of the lower cross bar 16 and the webs of the lower halves of the muntins 13 and 14 of the pivoted sash will contact with the flange 24 of this 15 lower channel bar 26; and that the outwardly extending flanges 20 of these bars 13, 14 and 16 will contact with the flange 25 of this lower channel bar. This results in a 20 double contact all around the pivoted sash, and prevents rain and snow from passing between the sashes.

Many changes in the construction of this window may be made by those skilled in this 25 art without departing from the spirit of my invention as set forth in the following claims.

I claim—

1. In a window, the combination of an 30 apertured main sash having a flange extending into the aperture at all sides, a ventilator sash within the aperture and having an exterior flange in the same plane as the flange on the main sash, a channel bar extending 35 partially around within said aperture and secured to the main sash and having its ends forming bearings, and a second channel bar extending partially around and secured to the outside of the ventilator sash above the 40 ends of the other bar and having its lower ends forming pivots for said ventilator sash which rest in said bearings.

2. In a window, the combination of a main sash having an aperture, a ventilator sash 45 within the aperture, a channel bar secured to the main sash within the aperture and a second channel bar secured to the outer edges of the ventilator sash, the ends of said bars forming pivots and bearings for said ventilator sash.

3. In a window, the combination of a main sash having an aperture, a ventilator sash within the aperture, a flanged bar secured to the main sash within the aperture 55 and a second flanged bar secured to the outer edges of the ventilator sash, the ends of said bars contacting and forming pivots and bearings for said ventilator sash.

4. In a window, the combination of a main 60 sash having an aperture, a ventilator sash within the aperture, a flanged bar secured to the main sash within the aperture and a second flanged bar secured to the outer edges

of the ventilator sash, the ends of said bars contacting and forming pivots and bearings 65 for said ventilator sash, and a screw mounted in the main sash on each side of the ventilator sash and engaging said ventilator sash to position it.

5. In a window, the combination of a 70 main frame formed with an aperture, a sash pivoted within the aperture, channel bars between the sides of the sash and the frame, the channel bar at each side consisting of two sections, one section being attached to 75 the sash and the other to the frame, the ends of the sections contacting and forming bearings for the pivoted sash.

6. In a window, the combination of a main frame formed with an aperture, a sash 80 pivoted within the aperture, channel bars between the sides of the sash and the frame, the channel bar at each side consisting of two sections, one section being attached to the sash and the other to the frame, the ends of 85 the sections contacting and forming bearings for the pivoted sash, the flanges of each section being of unequal width, and both flanges of each section adapted to contact with an opposite part of the window when the sash 90 is in the plane of the main frame.

7. In a window, the combination of a main frame formed with an aperture, a sash pivoted within the aperture, flanges on the frame and sash extending toward each other, 95 channel bars between the sides of the sash and the frame, the channel bar at each side consisting of two sections, one section being secured to the sash and the other to the frame, the ends of the sections contacting 100 and forming bearings for the pivoted sash.

8. In a window, the combination of a main frame formed with an aperture, a sash pivoted within the aperture, channel bars between the sides of the pivoted sash and 105 frame, the channel bar at each side consisting of two sections, one section secured to the main frame and the other secured to the sash, the ends of said sections contacting and forming bearings for the pivoted sash, the 110 flanges of each section being of unequal width, those on the main frame extending toward the pivoted sash and those on the pivoted sash extending toward the main frame, each of the flanges of both sections 115 contacting with an opposite part of the window when the pivoted sash is in the plane of the main frame.

In testimony whereof I have signed this specification in the presence of two subscribing 120 witnesses.

GUSTAVE KAHN.
